UNITED STATES PATENT OFFICE.

HANS HEINRICH AUGUST SIEVERS, OF DAVENPORT, IOWA.

MECHANICAL MOVEMENT.

No. 853,478.

Specification of Letters Patent.

Patented May 14, 1907.

Application filed September 20, 1904. Serial No. 226,270.

To all whom it may concern:

Be it known that I, HANS HEINRICH AUGUST SIEVERS, a citizen of the United States, residing at Davenport, in the county of Scott and State of Iowa, have invented new and useful Improvements in Mechanical Movements, of which the following is a specification.

This invention relates to a mechanical movement adapted to convert a continuous rotary motion into an alternating rotary motion such as is usually required for dashers or agitators of churning or washing machines, this invention being more particularly designed for use with the latter.

The object of the present invention is to increase the throw or rotation of the alternately driven member or agitator and to impart a variable speed thereto without increasing the diameter of the driving member which, in the present instance, consists of a continuously driven cam of varying pitch that rotates in a plane at right angles to the rotation of the driven member and actuates the latter through the medium of a reciprocating rack. The rack meshes with a gear on the driven member and carries a slide which engages a duplex peripheral cam groove in the driving member. By providing this duplex cam considerable rotation is imparted to the agitator shaft while the diameter of the cam is not increased.

For a full understanding of the detail construction, merits and advantages of my invention, reference is to be had to following description and the accompanying drawing in which:

Figure 1, is a perspective view of the mechanism mounted on the lid or cover of a washing machine. Fig. 2, is a plan view. Fig. 3, a transverse section on the line x—x of Fig. 2; and Fig. 4 is a detail in perspective of the slide which is carried by the rack.

Making renewed reference to the drawings wherein like characters of notation indicate corresponding parts appearing in the several illustrations, and reference being had thereto. 1 designates the lid or cover of a washing machine, and 2 a frame which is provided with integral uprights or standards 3, 4 and 5 each of which has a bearing for the driving shaft of the driving cam hereinafter to be referred to.

Journalled in a boss 6 of the frame is the

vertical driven shaft 7 of a washing machine 55 agitator or churn dasher and on its upper end is rigidly secured a pinion 8.

Secured to the lid or cover 1 on one side of the frame, and extending parallel therewith is a guide or grooved way 9, in which the rack 10 is reciprocally mounted. This rack has a base 11, provided with lateral flanges or wings 12, which engage with the grooves of the guide, and its rack bar or toothed portion 13 meshes with the pinion 8. This rack 55 is also provided with a vertical standard 14 in the upper end of which is a transverse bore 15; and journaled in the bore is a stud 16 having a slide-block 17 on its inner end. This slide block is of oblong shape and preferably concave on its outer face to conform to the periphery of the rotary driving drum with which it co-operates, and its sides are convex as at 18 for the purpose hereinafter described. A roller 14^a is journaled in the 75 standard and engages the slide to reduce friction.

19 designates a drum which is pierced by a driving shaft 20 that has its bearings in the uprights 3, 4 and 5 of the frame, the drum 80 being mounted between uprights 3 and 4 and held against longitudinal movement thereby, but adapted to be continuously rotated with the said shaft which is provided on its outer end with a balance wheel 21 that carries a 85 crank handle 22. Obviously, the shaft may be driven by belt and pulley or gearing or the like. This drum 19 is formed with a duplex-peripheral-cam groove 23 in which the slide block 17 rides when the drum is rotated and 90 inasmuch as the side faces of the cam groove are necessarily curved, the convex side faces of the slide will readily conform to such curvature, especially at the ends of the drum where the curve of the groove is accentuated. 95 The course of the cam groove is such as to describe two parabolic curves which intersect at the center of the drum on one side thereof, as at 24, and since the slide block is longer than the width of the groove it will 100 pass the intersecting groove without interference.

From the description thus far given, it will be understood that when the drive shaft 20 is continuously rotated it will also rotate 105 the drum 19 the groove of which is engaged by the slide block 17 and cause the slide to ride around the groove; the direction of the

slide being indicated by arrow *a* in Fig. 2. This movement will of course slide the rack 10 longitudinally in its guide 9 and the rack bar being in mesh with the pinion 8, the 15 latter will be rotated. It will also be seen that during one revolution of the "drum" 19, the rack bar 13 will be moved in one direction, and upon the next revolution the rack bar will be moved in the reverse direction. 20 The cam is of such shape that it imparts a variable speed to the rack bar and the dasher-shaft, and this by virtue of the double 25 parabolic curve that it describes. The cam groove at the ends of the drum is almost at right angles to the axis thereof, but gradually extends upwardly at an incline toward the axis as at *b*, until it reaches the center 24 of the drum where it intersects the return groove and then extends downwardly on the 30 opposite side at the same incline, as at *c*, until it reaches the bottom at the other end of the drum, the curve at such point being substantially at right angles to the longitudinal axis of the drum. The groove then 35 extends up the other side of the drum, as at *d* crosses the first mentioned groove at 24 and follows down the opposite side as at *e* where it joins the portion *b* at the end of the drum. By this construction the rack will 40 travel faster during the traverse of the slide block in the inclined portions of the groove and slower when the block is near the ends of the drum so that there will be a variable speed imparted to the rack and the driven 45 shaft 7, each shaft gradually coming to a standstill at the end of each alternate rotation or stroke.

Having thus described my invention, what I claim and desire to secure by Letters Patent is:

1. A mechanical movement embodying a continuously rotated driving member, a reciprocatory rack bar having a slide swiveled therein adapted to engage the driving member, an alternately rotated driven member having a pinion engaged by the rack bar, and means formed on the driving member to impart a variable speed to the rack bar and driven member.
2. A mechanical movement embodying a continuously rotated driving member having a duplex peripheral cam groove, a reciprocatory rack bar provided with a slide block adapted to engage the cam groove, and an

alternately rotated driven member having a pinion with which the rack-bar engages.

3. A mechanical movement comprising a continuously rotated driving drum having a duplex peripheral cam groove that describes two parabolic curves each of which terminates and joins at the center on one side of the drum, a rack bar a slide block swiveled therein adapted to engage with the cam groove, and an alternately rotated driven shaft a pinion which engages with the rack bar.

4. A mechanical movement for washing machines embodying a driven shaft a pinion thereon, a grooved guide secured to the machine, a rack bar slidably mounted in said guide and having a rack in engagement with the pinion and also having a vertical standard extending above the pinion, a slide block swiveled in the standard and projecting laterally therefrom, and the continuously rotated grooved cam engaged with the slide block, substantially as specified.

5. A mechanical movement for washing machines, embodying a driven shaft, a pinion thereon, a rack bar engaging the pinion, a slide carried by the rack bar, and a driving member having a cam groove engaged by the slide and constructed and arranged to impart a variable speed to the rack and the driven shaft.

6. A mechanical movement for washing machines, embodying a driven shaft, a pinion thereon, a rack bar engaging the pinion, a slide carried by the rack bar, and a driving member having a slide-engaging-surface of such shape as to reciprocate the rack with a gradually diminishing and increasing speed at the end and beginning of each stroke respectively.

7. A mechanical movement for washing machines, embodying a driven shaft, a pinion thereon, a rack bar engaging the pinion, an oblong slide block swiveled in the rack bar and having convex sides, and a driving member having a duplex peripheral cam groove engaged by the slide block.

In testimony whereof I affix my signature in the presence of two subscribing witnesses.

HANS HEINRICH AUGUST SIEVERS.
